W. L. FOURNIER

BRAKE BAND

Filed Sept. 9, 1922

Patented Jan. 15, 1924.

1,480,717

UNITED STATES PATENT OFFICE.

WILLIAM L. FOURNIER, OF SEATTLE, WASHINGTON.

BRAKE BAND.

Application filed September 9, 1922. Serial No. 587,108.

To all whom it may concern:

Be it known that I, WILLIAM L. FOURNIER, citizen of the United States, residing at Seattle, in the county of King and State of Washington, have invented certain new and useful Improvements in Brake Bands, of which the following is a specification.

This invention relates to an improved brake band, being particularly designed for use in connection with the service brakes of motor vehicles, and seeks, as one of its principal objects, to provide a brake band which will eliminate overheating and wherein wear will be reduced to a minimum.

15 A further object of the invention is to provide a band which will dispense with the usual band lining and wherein, in lieu of such a lining, a plurality of gripping rollers will be employed.

20 And the invention has as a still further object to provide a device wherein the rollers may be easily kept lubricated.

Other and incidental objects will appear hereinafter.

25 In the drawings:

Figure 1 is a side elevation of my improved brake band shown in connection with an ordinary brake drum, parts being broken away and illustrated in section,

30 Figure 2 is a fragmentary rear elevation of the device,

Figure 3 is an enlarged sectional view on the line 3—3 of Figure 1, looking in the direction of the arrows,

35 Figure 4 is a fragmentary sectional view on the line 4—4 of Figure 1, looking in the direction of the arrows, and

Figure 5 is a fragmentary section on the line 5—5 of Figure 1, looking in the direction of the arrows.

Referring now more particularly to the drawings, it will be seen that my improved brake band is formed of companion upper and lower segmental sections A and B, each comprising a pair of spaced arcuate side bars 10. Interposed between said side bars at the rear ends of the sections is a coupling block 11 to which the bars are pivotally connected by pins 12 and rising from said block 50 at its outer side is a sleeve 13. The block 11 serves, of course, to space apart the side bars of each pair at their rear ends and interposed between the forward ends of said pairs of bars are spacing blocks 14 and 15 respectively. These blocks are secured in position by rivets or other suitable fasten-

ing devices 16 extending through the side bars and rigidly connecting the bars of each pair at suitably spaced points are cross pins 17. Rising from the block 14 are spaced ears 18 and pivoted at one end between said ears is an upstanding operating lever 19. Rising from the block 15 is a lug 20 and pivotally connected to said lever is a toggle rod or link 21 extending freely through said lug. Threaded upon the rod to coat with the lug is a nut 22 and surrounding the rod is a spring 23 acting to spread the forward ends of the sections of the band, the nut 22 being adjustable for tensioning said spring.

Lying between the side bars of the sections is a plurality of gripping rollers 24 provided at their ends, as shown in Figure 3, with trunnions 25 journaled through the bars. These rollers are arranged relatively close together and project at the inner edge of the side bars, the peripheral surfaces of the rollers being preferably knurled. Formed in the outer edges of the side bars of the section A are, as particularly shown in Figures 2 and 5, longitudinally directed lubricant channels 26 and leading from said channels through said bars to the trunnions of each of the rollers upon said section are 35 passages 27. Overlying the outer edges of the side bars of both of the sections A and B are cover plates 28, the plate upon the section A closing the channels 26 throughout the major portion of their length. As 40 shown in Figure 1, the plates 28 are provided at spaced points with depending lugs 29 lying flat against the outer faces of the side bars of the sections and extending through said lugs are screws 30 threaded into the side bars for detachably connecting the cover plates thereto, the plates serving to house the rollers 24. Connected to the outer edges of the side bars of the section A at a point midway between the ends of said section is, as shown in detail in Figure 5, a cross plate 31 having a passage 32 therein communicating with the channels 26 in said bars and mounted upon said plate to communicate with said passage is an appropriate lubricant cup 33. Thus, lubricant introduced into the cup 33 will flow through the passage 32 to the channels 26 when the lubricant will flow along said channels to enter the passages 27 for lubricating the trunnions of the rollers upon the section A. Formed in the inner edges of the side bars

of the section B are, as shown in Figures 3 and 4, lubricant channels 34 closed by cover plates 35 secured to the inner edges of said bars and leading from said channels to the trunnions of each of the rollers upon said section are passages 36. Secured to the outer edges of said side bars near the ends of the section are cross plates 37 having passages 38 therein communicating with passages 39 leading through the bars to the channels 34 and mounted upon said plates to communicate with the passages 38 are appropriate lubricant cups 40. Thus, lubricant introduced into these cups will flow through the passages 38 and through the passages 39 to enter the channels 34, when the lubricant will flow through the passages 36 for lubricating the trunnions of the rollers upon the section B. All of the rollers may accordingly be easily maintained lubricated.

In Figure 1 of the drawing, I have shown my improved brake band in connection with a conventional motor vehicle brake drum 41. As will be observed, the sections of the band are formed to surround said drum while the sleeve 13 on the block 11 is adapted to accommodate the usual stud or post 42 for rigidly supporting the band in operative position. The rollers 24 will thus be sustained to coact with the drum 41 so that when the lever 19 is rocked forwardly by the usual mechanism, the band will be contracted and the rollers caused to grip the drum for braking the vehicle. On the other hand, when the pull upon the lever is released, the spring 23 will operate to spread the sections of the band at their free ends so that the rollers will be caused to release the drum. I accordingly provide a brake band of particularly efficient construction and since the gripping rollers of the device are mounted to freely revolve, wear will be reduced to a minimum.

Having thus described the invention, what is claimed as new is:

1. A brake band including companion pivoted rigid sections, and gripping rollers journaled upon the sections to coact with a brake drum.

2. A brake band including companion pivoted sections, and gripping rollers journaled upon the sections to coact with a brake drum, each of the sections being pro-

vided with means for distributing a lubricant to the journals of the rollers.

3. A brake band including companion pivoted sections each having spaced side bars, and gripping rollers journaled upon said side bars to coact with a brake drum, the side bars being formed with means for distributing a lubricant to the journals of the rollers.

4. A brake band including companion pivoted sections each having spaced side bars, and gripping rollers journaled upon said side bars to coact with a brake drum, the side bars being formed with lubricant channels having passages leading therefrom to the journals of said rollers.

5. A brake band including companion pivoted sections each having side bars, gripping rollers provided at their ends with trunnions journaled in said side bars, the side bars being formed with lubricant channels having passages leading therefrom to the trunnions of said rollers, and lubricant cups feeding said channels.

6. A brake band including companion pivoted sections each having side bars, gripping rollers provided at their ends with trunnions journaled in said side bars, the side bars being formed with lubricant channels having passages leading therefrom to the trunnions of said rollers, and cover plates overlying said bars housing the rollers.

7. A brake band including companion pivoted sections each having side bars, gripping rollers provided at their ends with trunnions journaled in said side bars, the side bars being formed at certain of their edges with lubricant channels having passages leading therefrom to the trunnions of said rollers, cover plates overlying said bars closing said channels, cross plates extending between the bars and provided with passages communicating with the channels, and lubricant cups carried by said cross plates to communicate with the passages therein.

8. A brake band including companion pivoted rigid sections, gripping rollers journaled upon the sections to coact with a brake drum, and cover plates carried by the sections housing the rollers.

In testimony whereof I affix my signature.

WILLIAM L. FOURNIER. [L.S.]
